[57] CLAIM

The ornamental design for a tool for twisting studs and the like, as shown and described.

DESCRIPTION

FIG. 1 is an isometric view of a tool for twisting studs and the like showing my new design.

FIG. 2 is a front elevational view of the tool for twisting studs and the like of FIG. 1.

FIG. 3 is a right side elevational view taken in the direction of arrow 3 of FIG. 2.

FIG. 4 is a top plan view taken in the direction of arrow 4 of FIG. 2.

FIG. 5 is a bottom plan view taken in the direction of arrow 5 of FIG. 2.

The rear elevational view is identical to the front elevational view of FIG. 2.

The left side elevational view is identical to the right side elevational view of FIG. 2.
